US0D1068502S

(12) United States Design Patent (10) Patent No.: US D1,068,502 S
(45) Date of Patent: * Apr. 1, 2025

(54) WATCH CASE

(71) Applicant: Tiffany & Co. Swiss Watches Sàrl,
Meyrin (CH)

(72) Inventor: Emmanuel Gueit, Geneva (CH)

(73) Assignee: Tiffany & Co. Swiss Watches Sàrl,
Meyrin (CH)

() Term: 15 Years

(21) Appl. No.: 35/518,809

(22) Filed: Jul. 25, 2023

(80) Hague Agreement Data

Int. Filing Date: Jul. 25, 2023

Int. Reg. No.: DM/232433

Int. Reg. Date: Jul. 25, 2023

Int. Reg. Pub. Date: Oct. 27, 2023

(30) Foreign Application Priority Data

Apr. 28, 2023 (CH) 2023-00251

(51) LOC (15) Cl. 10-02

(52) U.S. Cl.

USPC D10/38; D10/122; D10/126
